UNITED STATES PATENT OFFICE

165,789

MUSICAL HAIRBRUSH OR SIMILAR ARTICLE

Celia Robbins, New York, N. Y.

Application November 25, 1950, Serial No. 13,127

Term of patent 7 years

(Cl. D56—1)

To all whom it may concern:

Be it known that I, Celia Robbins, a citizen of the United States, and a resident of New York city, New York, have invented a new, original, and ornamental Design for a Musical Hair Brush, or Similar Article, of which the following is a specification, reference being had to the accompanying drawing, forming a part hereof, in which

The dominant features of the design reside in the portions shown in full lines.

I claim:

The ornamental design for a musical hair brush or similar article, as shown and described.

CELIA ROBBINS.
